UNITED STATES PATENT OFFICE.

HARRY H. KNEPPER, OF DETROIT, MICHIGAN.

SPRING CUSHION OR MATTRESS.

Application filed April 18, 1921. Serial No. 461,990.

To all whom it may concern:

Be it known that I, HARRY H. KNEPPER, a citizen of the United States, residing at Detroit, county of Wayne, State of Michigan, have invented a certain new and useful Improvement in Spring Cushions or Mattresses, and declare the following to be a full, clear, and exact description of the same, such as will enable others skilled in the art to which it pertains to make and use the same, reference being had to the accompanying drawings, which form a part of this specification.

This invention relates to spring structures for cushions, mattresses etc., and the object is to provide a simple and inexpensive construction for building up the spring body of a cushion or the like and in which the springs are held under tension in separate rows, each row being held in an individual container therefor with the springs of each row connected together in hinged relationship. A further object of the invention is to provide a spring structure in which the springs are in rows with each row in a separate container and further to provide, with the group of containers, top and bottom frames secured to the fabric of the containers in a manner to maintain the springs in the desired assembled relation. Heretofore, it has been usual to provide containers for the individual springs but this results in a comparatively expensive structure which is avoided by providing a cheaply made separate container for each row of springs as hereinafter described. These and other objects and novel features of construction are hereinafter more fully described and claimed, and the preferred form of construction of a cushion or mattress embodying my invention is shown in the accompanying drawings in which—

Fig. 1 is a plan view partly broken away showing my improved spring structure and upper border frame and secondary frame secured to the fabric and containers for the springs.

Fig. 2 is a section taken on line 2—2 of Fig. 1.

Fig. 3 is an elevation showing the spring and its container as used in the structure.

Fig. 4 is a cross section of one of the fabric containers before the springs are inserted therein.

Fig. 5 is a side elevation thereof.

In the structure herein disclosed I form a

container of burlap or other fabric of the desired character which is folded upon itself and the edges sewed together as indicated in Figs. 4 and 5. This type of container may be very cheaply made of a single piece of fabric and run in continuous strips through the proper type of sewing machine forming a tube and the fabric tube may be cut in the desired lengths depending upon the size of the spring structure to be made.

The springs, as will be understood from Fig. 2, are of coil type and preferably the several turns of the coils are all of the same diameter. These coils are hingedly connected together by means of a clip 2 which may be of any approved type permitting the upper and lower coils of adjacent springs to hinge or turn relative to one another such for instance as is shown in Letters Patent of the United States to O. R. Hunt, No. 1,262,196 of April 9, 1918. The character of clip, however, is not deemed essential to this invention, the particular feature being the type of container and the means for securing the several containers in assembled relation. The bag or container made in the general manner indicated in Figs. 4 and 5 is such that when the row of springs is inserted therein the springs are held under some compression therefore tending at all times to hold the fabric 3 taut as indicated in Fig. 3.

The containers are assembled together in rows as will be understood from Fig. 1 with the springs of one container preferably in staggered relation with those of an adjacent row so that the several containers are closely nested together practically closing the space between the rows to prevent material (such as padding or the like usually placed thereon) from creeping downward in between the rows in subsequent use of the cushion or mattress. To hold the several rows together in the desired assembled relation, I provide a border frame such as is indicated at 4 in Fig. 1 defining the outline of the cushion or mattress and here shown as being rectangular in form. There is a lower and an upper border frame of similar form and both frames are sewed or tied to the fabric of the containers as indicated at 5 in Fig. 1. In fact the seam 1 of each of the containers is indicated on the upper surface of the structure, but it is immaterial which end of the springs is placed uppermost or whether or not the seam of the container

is on the upper or lower side of the completed cushion.

As will be readily understood, the assembled structure is enclosed within a leather or other character of finishing material cover and usually padding is introduced between the spring body and outer covering which is not here shown. With a border frame as indicated defining the outline of the cushion or mattress, any one sitting upon the edge of the cushion will deflect a considerable number of springs due to the action of the border frame. Preferably I use a secondary frame 6 on the top of the structure 10 as shown in Fig. 1 which is hingedly connected to the rear edge of the upper border frame 4 as indicated at 7, 7. This frame extends forward toward the front of the cushion and with the sides and front of the frame 6 spaced from the border frame overlying the springs spaced from the border springs engaged by the border frame. This frame 6 is a strengthening member and serves to bring into play a considerable number of springs within the containers when deflected by a person sitting or lying thereon but, due to its being hinged to the border frame at the rear edge only and otherwise unconnected with the border frame it has an 20 action practically independent of the border frame. With the border frame sewed to the fabric of the containers, displacement of the containers and of the springs therein is prevented and the same are held in close relationship.

In Fig. 2 I have shown a cross section of a cushion or mattress and in full lines the structure is shown to be of equal height from front to back. However, if it is desired that the cushion be higher at the front than at the back, containers of greater height may be used at the forward edge of the cushion and containers of successively less depth be provided for the succeeding rows of springs as will be readily understood. The dotted line *a* indicates a structure in which the forward edge of the cushion is of greater depth than the rear edge and the dotted line *b* indicates a structure in which it is of 40 greater depth at the center than either at the front or rear edge and this is secured by provision of containers of varying width adaptable to produce the desired result.

By the arrangement described the several

rows of springs are separated by two thicknesses of the fabric or material of which the containers are formed and the coils of the springs of one row do not become interlaced with the coils of the springs of an adjacent row. This is particularly due to the fact that the containers are less in depth than the normal length of the springs. The springs therefore maintain the fabric taut and prevent the springs from intermeshing. If the fabric containers were sufficiently loose the springs could, by reason of such looseness, become intermeshed causing a partial collapse of the spring structure which is avoided by the means described. The principal features of this invention 65 therefore are the separate containers for the rows of springs in which the springs of each row are hingedly connected together; the means for maintaining the containers in assembled relationship, as described consisting 70 of frame members at the top and bottom tying the several containers in place and in which the springs are held under compression by the containers, and the secondary frame free to move independently of the 75 border frame and sustained by springs spaced from those sustaining the border frame.

Having thus fully described my invention, what I claim and desire to secure by Letters Patent of the United States is—

In a cushion or mattress, a resilient body comprising a plurality of rows of coiled springs, the springs of each row being hingedly connected together, a separate fabric 90 container for each row, the springs being normally of greater length than the depth of the container whereby the fabric of the container is held taut, and means for holding the several rows in assembled relation comprising a top and bottom border frame 95 defining the outline of the cushion or mattress secured to the fabric containers and overlying the border springs of the group, and a secondary frame within the upper border frame overlying the springs adjacent the border springs and hingedly connected with the upper border frame at one side only.

In testimony whereof, I sign this specification.

HARRY H. KNEPPER.
